UNITED STATES PATENT OFFICE.

MORRIS WISE, OF NEW YORK, N. Y.

INTERCHANGEABLE HEEL.

SPECIFICATION forming part of Letters Patent No. 487,312, dated December 6, 1892.

Application filed August 20, 1891. Renewed June 8, 1892. Serial No. 435,943. (No model.)

To all whom it may concern:

Be it known that I, MORRIS WISE, a citizen of the United States, residing at New York, in the county and State of New York, have 5 invented new and useful Improvements in Interchangeable Heels, of which the following is a specification.

This invention relates to an improvement in heels for boots and shoes; and the invention 10 consists in the novel features of construction hereinafter described and claimed for making the heels interchangeable or readily removable and attachable, so that when a heel is worn or injured or the style of heel is to be 15 changed the heel in the boot or shoe can be readily removed and another substituted.

This invention is illustrated in the annexed drawings, in which—

Figure 1 is an inverted plan view of a sole 20 adapted to receive a heel. Fig. 2 is a plan view of a heel adapted to be secured to the sole shown in Fig. 1. Fig. 3 is a detail view of a key. Fig. 4 shows the key applied to use. Fig. 5 is a section along xx , Fig. 4. Fig. 25 6 is a section along yy , Fig. 4. Fig. 7 is an inverted plan view of a sole with a modified form of attaching device. Fig. 8 is a plan view of a heel adapted to be secured to the sole shown in Fig. 7. Fig. 9 shows a key 30 adapted for use with the heel of Fig. 8. Fig. 10 shows the key of Fig. 9 applied to use. Fig. 11 is a section along zz , Fig. 10. Fig. 12 is a section along ww , Fig. 10. Fig. 13 is a longitudinal section of a modification.

35 In the drawings, the letter A indicates the sole to which the heel is to be attached, and B is the heel. To the sole is secured a plate C, having eyes D, and the heel is provided with a plate E, having eyes F. When the 40 heel is placed in position, the eyes D F are in alignment, and by inserting the key G in place, so as to engage the eyes D F, the heel is secured in place. The key G has an eye H, into which can be inserted an awl, hook,

or other suitable tool for withdrawing the key 45 when the heel is to be removed. In order that the position of the heel can be easily fixed, pegs or projections I, engaging suitable eyes or depressions K, can be provided, and by means of these pegs the key G is also relieved from considerable lateral strain while 50 the wearer is walking.

In Figs. 7 to 12 the plates C E are shown as having each a double row of eyes D F, and the key G, Fig. 9, has two branches for engaging said eye-rows.

The key in Figs. 1 to 12 is inserted and withdrawn at the back; but by making the channel or passage for the key extend from the back through the breast of the heel, as 60 seen in Fig. 13, the key can be passed into place at the back and then pushed through and withdrawn at the breast, or vice versa.

The heel can be attached to the sole or quarter, as in Figs. 1 to 12, or a lift L can be 65 secured to the sole or quarter, as in Fig. 13, and the heel B attached to this lift.

What I claim as new, and desire to secure by Letters Patent, is—

The sole A, having the attached plate C 70 struck up with the series of outwardly-projecting eyes D, in combination with the heel B, having the attached plate E arranged on its upper surface and provided with the series of struck-up eyes F, which pass between 75 the eyes of the sole-plate, and the lengthwise-sliding key G, composed of a flat rectangular plate inserted through the struck-up eyes of the two plates, substantially as shown and described.

In testimony whereof I have hereunto set my hand in the presence of two subscribing witnesses.

MORRIS WISE.
